UNITED STATES PATENT OFFICE.

BENJAMIN H. SEYMOUR, OF OCALA, FLORIDA.

CROSS-TIE HEWER AND VENEER-MILL.

SPECIFICATION forming part of Letters Patent No. 762,205, dated June 7, 1904.

Application filed November 23, 1903. Serial No. 182,340. (No model.)

To all whom it may concern:

Be it known that I, BENJAMIN H. SEYMOUR, a citizen of the United States, and a resident of Ocala, in the county of Marion and State of Florida, have made certain new and useful Improvements in Cross-Tie Hewers and Veneer-Mills, of which the following is a specification.

This invention is an improvement in wood-working-machines, and especially in machines of the nature of cross-tie hewers and veneer-mills, whereby the ties may be readily brought to the desired shape or veneers can be cut as may be desired; and the invention consists in certain novel constructions and combinations of parts, as will be hereinafter described and claimed.

In the drawings, Figure 1 is a front elevation of a machine embodying my invention. Fig. 2 is a top plan view thereof. Fig. 3 is an end elevation. Fig. 4 is a detail rear elevation of the log-clamp. Fig. 5 is a detail section on about line 5 5 of Fig. 4. Fig. 6 is a detail perspective view of the log-clamping jaw. Fig. 7 is a detail section on about line 7 7 of Fig. 2, and Fig. 8 is a detail section on about line 8 8 of Fig. 3.

In carrying out my invention I employ a suitable framing having base-beams A, upright beams B, top beams C, and a bed D, on which the logs may be moved toward the cutter by the carriage K presently described. In the framing are journaled near its opposite ends crank-shafts F and G, having cranks f and g, which are connected by the pitmen F' and G' with the opposite ends of the knife H. The knife H comprises the bar H' and the blade H² and operates at one end between the guide-bars I and at its opposite end between the guide-bars J, such guide-bars being spaced apart sufficiently to receive the knife between them and the guide-bars J being inclined from end to end and provided with longitudinal slots J', in which operate the projections J² on the knife. These projections may be provided with antifriction-rollers, as shown in Fig. 1, to reduce friction in the operation of the invention. As the crank-shafts F and G are turned in the same direction by the means presently described the knife H

what oscillating movement, so that it will cut with a shearing action, which is desirable in operating upon heavy logs. The crank-shafts F and G are provided, respectively, with gear-wheels F² and G², which are meshed by pinions f³ and g³ on counter-shafts F³ and G³, and these counter-shafts are provided with bevel-gears f² and g², which are meshed by bevel-gears i and i' at the ends of the connecting-shaft I. Power may be applied to drive the shafts, and this may be effected by the construction shown, in which a pulley J³ is clutched by a suitable form of clutch mechanism on the counter-shaft F³, the clutch mechanism having a lever J⁴, by which the pulley may be clutched on or released from the shaft F³, and this pulley J³ may be connected by belt-gearing with a suitable drive-power in any ordinary manner.

The carriage K for the logs is movable back and forth on the bed-sills D and is provided with suitable knees K' and at its ends with means for clamping the log. As shown, the log-clamps (see Figs. 4 and 5) comprise frames L, which are mounted on the carriage K and are provided with the jaws M for holding the logs. The frame L may, if desired, be slidably mounted on the carriage K, and means, such as set-screws L', (shown in Fig. 4,) may be employed to secure the frame L in any desired position upon the carriage K.

The jaws M are toothed at M' and have shanks M², slotted at M³, so they can be adjustably connected with the slides N, mounted in the frame L, and arranged to be adjusted by the screws O in order to force the jaws M into engagement with the log. The jaws M may by the slots M³ be adjusted in and out to suit logs of different sizes and may be secured in any desired adjustment by the screws M⁴, as will be understood from Fig. 4 of the drawings.

In practice it is desirable to feed the carriage K and the log forward toward the knife in correspondence with the operation of the knife, so that the log will be fed toward the knife after each operation of the latter. This may be effected by the construction shown in Figs. 2, 3, and 8. This includes transverse feed-screws P, journaled at P' to the main

frame and screwing at P^2 in connection with the carriage K, so that as they are turned in one direction or the other they will either advance or retract the carriage K, and these feed-screws P are provided with beveled pinions P^3 , which are meshed by beveled pinions Q' on the feed-shaft Q. (See Fig. 2.) This feed-shaft is provided with a pinion Q'', which is meshed by a toothed wheel R, and the latter is engaged by pawl devices S' on a swinging arm S, which arm swings concentrically with the toothed wheel R and is connected by a link or pitman S² with one end of the lever S³, the other end of which lever is connected by a link S⁴ with a rocker S⁵, pivoted between its ends at S⁶ and arranged at its other end to be engaged and operated in one direction by a pin or projection S⁷ in a hub S⁸ on the crank-shaft G, the rocker S⁵ being operated by a spring S⁹ in opposition to the projection S⁷, as best shown in Fig. 8 of the drawings. By using pins S⁷ of different lengths and employing a pin of the desired length in each case, to which end the pins are made interchangeable by threading them at one end at S¹⁰ into the hub S⁸, as shown in Fig. 8, will vary the throw of the rocker S⁵ and so cause the swinging arm S to move its pawl to such extent as to move the toothed wheel R different distances at each step-by-step operation of the rocker.

The described construction will be found efficient in moving the logs step by step. It may, however, be desired to feed the log more rapidly, and it will also be found desirable to quickly retract the carriage. To this end I employ mechanism independent of the step-by-step devices and which must be brought into play by the means presently described, it being understood that when such independent feed mechanism is brought into operation the pawls S' on the swinging arm S should be moved out of engagement with the tooth R, which may be effected by throwing said pawls back, or, if desired, any of the connections between the swinging arm S and the rocker may be disconnected, or the pin S⁷ may be screwed out of the hub S⁸.

The independent feed mechanism includes a friction-disk T on the connecting-shaft I', meshed with a friction-pulley T' on a transverse shaft at T'', which shaft is also provided with a friction-pulley T'', which extends adjacent to the feed-shaft Q. This feed-shaft is provided with two friction-disks U and U', which are keyed on and slidable along the feed-shaft Q and extend on opposite sides of the friction-pulley T'' and may be brought alternately into engagement with said pulley T'' by means of the shifting devices U² and U³, as shown in Figs. 2 and 7, or may be brought to a neutral position in which the pulley T'' will not drive either one of the disks U and U'. In the position of parts shown in Fig. 7 the pulley T'', bearing against the pulley U, will

turn the latter and the shaft Q in one direction, and if the disks U and U' should be shifted to free the disk U from engagement with the pulley T'' and to move the disk U' into engagement with the pulley T'' the shaft Q will be turned in the opposite direction. From this it will be seen the disks U and U' may be manipulated to cause the pulley T'' to turn the feed-shaft Q in one direction or the other or to such a position that the pulley T'' will not operate the feed-shaft Q at all. This independent feed mechanism will be found useful in rapidly retracting the carriage as well as in securing a rapid advance movement of the carriage whenever such operation is desired.

Having thus described my invention, what I claim as new, and desire to secure by Letters Patent, is—

1. The improved machine substantially as herein described comprising the framing, the knife, the guides for one end of the knife, the keeper-guides for the other end of the knife and provided with longitudinal inclined slots, the projections on the knife operating in said slots, the opposite crank-shafts journaled in the framing, the pitmen connecting the cranks of said shafts with the opposite ends of the knife, counter-shafts geared with the crank-shafts, a connecting-shaft geared with the crank-shafts, the log-carriage provided with clamps for securing the logs, the feed-screws journaled to the framing and having threaded engagement with the carriage, the feed-shaft, gearing between the feed-shaft and the feed-screws, the disks keyed on and movable along the feed-shaft, the transverse shaft having a friction-pulley at one end extending between the disks of the feed-shaft and a friction-pulley at its other end, a friction-disk on the connecting-shaft engaging with said friction-pulley on the transverse shaft, a toothed wheel for turning the feed-shaft step by step, a swinging arm having pawl devices engaging said toothed wheel and intermediate devices between said swinging arm and one of the crank-shafts whereby to operate the feed-shaft step by step relatively to the movement of the crank-shafts substantially as set forth.

2. The combination with the framing and the knife and the guides for the knife, of the opposite crank-shafts, the pitmen connecting the cranks of said shafts with the knife, the counter-shafts geared with the crank-shafts, the connecting-shaft geared with the counter-shafts, a carriage provided with means for holding a log, a feed mechanism for the carriage, devices whereby said feed mechanism will be operated from one of the crank-shafts, and independent feed mechanism, and means for operating the latter from the connecting-shaft substantially as set forth.

3. In a machine substantially as described the combination with the frame, the knife and the crank devices for operating the knife, of

the shafts carrying said crank devices, a connecting-shaft, gearing between the connecting-shaft and the crank-shafts, the carriage, the feed-screws for the carriage, a feed-shaft 5 geared to the feed-screws, disks keyed on and movable along the feed-shaft, a transverse shaft, a friction-pulley at one end of said transverse shaft and projecting between the disks of the feed-shaft, friction-gearing be-

tween the transverse shaft and the connecting-shaft, an independent step-by-step feed mechanism and means for operating said independent feed mechanism from one of the crank-shafts. 10
